UNITED STATES PATENT OFFICE.

ROBERT W. GRAVES, OF ELIZABETH, NEW JERSEY, AND SAMUEL MIDDLETON HOLT, OF WASHINGTON, DISTRICT OF COLUMBIA; SAID HOLT ASSIGNOR TO SAID GRAVES.

SAW.

1,352,512.

Specification of Letters Patent. Patented Sept. 14, 1920.

Application filed April 25, 1919. Serial No. 292,649.

To all whom it may concern:

Be it known that we, (1) ROBERT W. GRAVES, a citizen of Canada, and (2) SAMUEL MIDDLETON HOLT, a citizen of the 5 United States of America, residing (1) at Elizabeth, (2) Washington, District of Columbia, in the county of (1) Union and (1) State of New Jersey, have invented certain new and useful Improvements in Saws, 10 of which the following is a specification.

The primary object of the present invention resides in the provision of a hand saw especially adapted for felling trees and cutting logs and timber, the construction being 15 such as to render the cutting operation easily and quickly accomplished by a single operator, the type of saw herein shown and described being of like character to the type of saw, shown, described and claimed in 20 Patent 1,127,883, granted to Robert W. Graves, February 9, 1915, and particularly relates to certain new and useful improvements thereover.

A further object of the invention is to 25 provide a hand saw that is adapted to remain in forceful engagement with the work, thus permitting the operator to devote his entire energies to the reciprocating cutting operation and rendering the severing of 30 elevated limbs and beams less arduous than under the usual circumstances of sawing, wherein it is necessary to force the saw into engagement with the work in addition to causing a reciprocatory movement thereof.

A still further object of the invention is 35 to provide a saw with a guiding means readily adjustable for accommodating work of different diameters, the saw being resiliently held into engagement with the work 40 until the completion of the sawing operation.

A still further object of the invention resides in the provision of a sawing device 45 having a measuring arm constituting a presser bar for the saw whereby the diameter of an object to be severed, as well as other measurements may be easily determined.

With these general objects in view the invention consists of the combination and arrangement of parts hereinafter fully described in connection with the accompanying drawings and in which like reference characters designate corresponding parts 50 throughout the several views.

In the drawings,

Figure 1 is a side elevation of the invention partially broken away and illustrated by dotted lines in its operative position adjusted for cutting a log,

Fig. 2 is an edge view of the same looking toward the rear of the saw,

Figs. 3, 4 and 5 are transverse sectional views taken upon lines III—III, IV—IV and V—V respectively of Fig. 1,

Fig. 6 is a detail view of the spring adjusting means,

Fig. 7 is a transverse sectional detail view taken upon line VII—VII of Fig. 1,

Fig. 8 is a view similar to Fig. 1, of a 70 different form of the invention,

Figs. 9, 10 and 11 are sectional views taken upon lines IX—IX, X—X and XI—XI respectively of Fig. 8,

Fig. 12 is an elevational view of a portion 75 of the invention shown in Fig. 8, with the guide at a different adjustment and the saw adjusted upon an extension and

Fig. 13 is a side elevation of a portion 80 of another modified construction adapted for sawing felled trees.

Referring more in detail to the drawings, our invention essentially comprises a handle frame having two hinged handle bars, 10 and 11 provided with a saw blade 12 adjustably carried by the bar 10 and a presser-bar guide 13 for the work adjustably carried by the bar 11 suitably spaced from and adapted to coöperate with the blade 12 for sawing the work such as the log 14.

The handle bars 10 and 11 taken with the rigid brace 15 carried at the forward end of the bar 10 constitute a substantially rectangular frame when said handle bars which are pivoted together at 16 are in their normally closed position. The brace 15 has a foot 17 adapted to engage the free end portion of the handle bar 11 while the outer end of the foot carries a post 18 parallel with the brace 15 for slidably mounting the 100 saw 12 thereon. The post 18 is in the form of a flat bar slidably positioned between parallel guides 19 secured to one face of the base or larger end of the saw 12, as shown in Fig. 1, with the cross piece 20 connecting said guides 19 and overlying the post 18, the saw 12 being adjustably supported on the foot 17 and secured in the desired position by a set screw 21 threaded through the cross piece 20 for engaging the post 18.

A resilient member in the form of a coil spring 21 is adjustably connected between the handle bars 10 and 11, having one end of the spring secured to a clip 22 upon the handle bar 10 while the other end of the spring is adjustably secured to the handle bar 11 by means of a locking plate 23 slidably mounted upon, the handle bar 11 and adapted for maintaining its position when 10 adjusted by canting slightly to bind upon the bar 11.

It will be understood that both handle bars 10 and 11 are preferably cylindrical in cross section and may be formed of tubing, 15 the rear end of the bar 10 preferably having an inclined section 24 for positioning beneath the arm of the operator when sawing lowered objects during which operation, the handle bars are grasped by the forward 20 grips 25 and 26 upon the handle bar 10.

A grip 27 is secured to the rear end of the section 28 of the handle bar 10 while the grip 29 is adapted to be grasped for use together with the grip 28 mounted upon the 25 handle portion 10 rearwardly of the handle 25. It will of course be apparent that any of said grips may be employed which will be more convenient to the operator for reciprocating the saw 12. The hand grip 26 30 has an adjustable mounting rod 30, permitting said grip to be turned inwardly as indicated by dotted lines in Figs. 1 and 4 of the drawings for convenience in packing or carrying the device.

35 A double triangular brace 31 connects the handle bar 10 with the block 17 and adjacent bar of the brace 15, and carries spaced pulley wheels 32 journaled therebetween and inwardly of said handle bars 10 and 11 with 40 the spring 21 mounted to travel thereover between the braces 31. A similar pulley wheel 33 is carried by a bracket 34 upon the handle portion 11 with the spring 21 running over the same, while depending ears 45 35 upon the braces 31 are guidingly placed at opposite sides of the roller 33 when the handle is closed as shown in Fig. 1 of the drawings.

50 The presser-bar guide 13 is in the form of a longitudinal arm having a shank 36 adjustably secured to a depending arm 37 at the free end of the handle bar 11 while a set screw 38 retains the same upon said arm. Suitable graduations 39 upon the guide 13 55 may be employed for measuring the diameter of the work 14.

When it is desired to saw an object such as the trunk of a tree and it being desired to leave two inches unsawed to be broken 60 off by the falling of the tree, the blade 12 and presser-bar guide 13 are adjusted upon the post 18 and arm 37 respectively to position the inner engaging edge 40 of the presser bar guide 13 and the toothed cutting edge 41 of the blade 12 substantially

two inches apart while the handle bars 10 and 11 are in closed position. On spreading the guide and blade against the action of the spring 21^a, the device is arranged to have the tree 14 positioned between the saw 70 guide as shown in Fig. 1 and reciprocated by grasping the grips 27 and 29 or 25 and 26. The drawing of the blade 12 and guide 13 toward each other by means of the spring 21 retains the teeth 41 in positive cutting 75 engagement with the work 14 without any effort on the part of the operator. The presser-bar guide edge 40 is slightly rounded and may form a groove upon one side of the tree 14 further insuring the uniformity 80 of the path of travel of the saw during the cutting operation and maintaining the horizontal alinement of the saw and guide.

The tension of the blade 12 upon the work is regulated by adjusting the plate 23 of 85 the spring 21 either toward the grip 27 to increase the tension or toward the bracket 34 to decrease the same. The brackets 42 of the grips 25 and 29 serve as guides through which the spring 21 extends.

90 The main elements of the form of the invention shown in Fig. 8 are similar in operation and structure to that heretofore described and provides two handle bars 10' and 11' hinged together as at 16' with a 95 spring 21' anchored to a clip 22' upon the bar 10' and passing over the rollers 32' and 33' carried by the handle bars 10' and 11' respectively with the other end of the spring secured to an adjusting plate 23' 100 upon the bar 11'. A grip 27' is provided on the rear end of the structure while intermediate hand grips 29' and 25' are carried by the bar 10'.

An arm 37' angularly projects from the 105 free end of the handle bar 11' for engagement by the free end of the handle portion 10' when normally in its closed position. A gage 13' is adjustably mounted by means of a shank 36' upon the arm 37' being secured in adjusted position by the set-screw 38'. A saw-blade 12' is adjustably mounted by means of a strap or bracket 43 upon the blade slidably mounted upon a post 18' carried by the free end of the handle bar 10' 115 outwardly thereof and in longitudinal alinement with the arm 37'. A set-screw 21' through the strap is adapted to bear upon the post 18' for securing the saw-blade 12' in its adjusted position, the said connection 120 being best illustrated in Figs. 8, 10 and 11 of the drawings. The handle bars 10' and 11' are separated against the action of the spring 21^a in the manner heretofore noted and as illustrated by dotted lines in Fig. 8, 125 the guide 13' having a longitudinal bearing rib 40' while the blade and guide are relatively adjusted for receiving the work in the manner set forth. A stop bar 44 is hinged as at 45 to the inner end of the 130

hand grips 25' and has an end 46 spanning the handle member 11' as well as the spring 21^a and slidably mounted thereon during the opening of the handle. The stop member 44 limits the extent to which the handle may be opened thereby limiting the size of work receivable between the blade 12' and guide 13'. The pivotal connection 16' is separable for detaching the handle member 11' and permitting the stop member 44 to be removed therefrom while the pivot 45 is also removable at will. This enables the changing of the stop member 44 for one of a different length, which is essentially serviceable where the law of the locality forbids the cutting of trees below a certain diameter and the provision of the stop 44 provides an automatic means for preventing the operator from cutting smaller trees than those permitted by law. Gage marks as 15 inch, 20 inch and 25 inch as shown on the bar 11' in Fig. 8 may be provided which will enable the operator to quickly determine whether the tree be below size or not. In Fig. 12, a portion of the invention set forth in Fig. 8 is illustrated but with the saw 12' adjustably mounted upon an extension 47' secured to the post 18' by such devices as screws 48. Rollers 49 and 50 are preferably journaled in the opposite ends of the end 46 of the bar 44 inwardly of the spring 21^a and outwardly of the handle bar 11' respectively.

For cutting up felled trees, it is sometimes advisable to have the cutting and presser-bar guide members positioned at an angle with respect to the handle and in Fig. 13 a portion of the invention as illustrated in Fig. 1 is set forth with the blade 12 and presser-bar guide 13" positioned at an angle to the handle bars 10-11. The saw 12' illustrated in Fig. 8, may be reversed upon the post 18' for bringing the teeth 41' adjacent the handle bar 10' whenever the saw is not in use or when transporting the same. In all of the forms of the invention, the saw blade and guide are readily removable as well as interchangeable to accommodate the device for varying conditions.

Upon turning the hand grip 26 inwardly, in the structure illustrated in Fig. 1, of the drawings, the blade 12 may be reversed upon the post 18 and the presser-bar guide 13 reversed upon the arm 37, so that the invention assumes a compact arrangement for packing and handling without danger of injury either to the device or the person carrying the same.

Attention is called to the fact that in the present device, the presser-bar is of such construction as to prevent same from flexing, and thus at all times exerts an even pressure to prevent any wobbling of the saw

during operation, and resulting in easy 65 working of the saw. In actual practice, we have found that by constructing this presser-bar of wood, in the form shown in Fig. 1, or of tube steel in the form shown in Fig. 8, and inserting the thin edge strip 70 40, the latter will indent into the bark of the tree or log and maintain this position, so that the easy working of the saw is assured.

What we claim as new and desire to secure by Letters Patent is:—

1. A saw comprising a handle frame of substantially rectangular form comprising two handle bars, pivotal connections between said handle bars at one end of the frame, an arm and a post in longitudinal alinement with each other carried by the separate handle bars at the opposite end of the frame, a presser-bar guide and a saw blade adjustably mounted upon said arm 85 and post projecting in opposite directions from said handle bars, rollers carried by each bar, a coil spring having one end thereof secured to one of said handle bars with the other end of the spring adjustably secured to the other handle bar and passing over said rollers whereby the resilient connection between the portions of the handle is adapted for adjustment at will, and the hand grips carried by one of said handle 90 portions.

2. A saw comprising handle bars pivotally connected together at one end, a presser-bar guide secured to one of said handle bars at the opposite end of the device, a saw 100 blade secured to the end of the other handle bar spaced from said guide adapted for the reception of the work between said blade and guide, pulley wheels journaled adjacent the forward portions of said handle portions, a coil spring secured to one of said handle bars passing over said pulleys with 105 its other end adjustably attached to the other handle bar.

3. A saw comprising handle bars pivotally connected together at one end, a presser-bar guide secured to one of said handle bars at the opposite end of the device, a saw 110 blade secured to the end of the other handle bar spaced from said guide adapted for the reception of the work between said blade and guide, pulley wheels journaled adjacent the forward portions of said handle portions, a coil spring secured to one of said handle bars passing over said pulleys with 115 its other end adjustably attached to the other handle bar, a plurality of hand grips rigidly secured to one of said handle bars and another hand grip adjustably mounted 120 upon the same handle bar adapted for partial rotation thereon.

4. A saw comprising a handle frame formed of pivotally connected bars, an arm

- carried by the free ends of one of said bars and a post carried by the free end of the other, the arm and post extending at right angles to the longitudinal axis of said frame
- 5 5. A saw comprising a handle frame mounted upon said arm, a saw blade and means adapted for mounting the blade upon said post at different distances from said guide when the handle is in its normally closed position.
- 10 5. A saw comprising a handle frame formed of pivotally connected bars, an arm carried by the free ends of one of said bars and a post carried by the free end of the other, a presser-bar guide mounted upon
- 15 said arm, a saw blade and means adapted for mounting the blade upon said post at different distances from said guide when the handle is in its normally closed position, a coil spring adjustably connected between
- 20 said handle bars to vary the tension thereon and anti-friction wheels carried by each of said handle-bars over which said spring is adapted to travel.
6. A saw comprising a handle frame
- 25 formed of bars pivotally connected together at one end of the device, a presser-bar guide and a saw secured to the adjacent ends of said handle bars, connecting means between said handle bars including a pivoted stop
- 30 having slidable connection with one of said handle bars and adapted for limiting the distance between said guide and blade when the handle is opened to the limit of its pivotal movement.
- 35 7. A saw comprising a substantially rectangular handle frame formed of two bars pivotally connected together at one end of the frame, a saw blade projecting from the unpivoted end of one of said handle bars,
- 40 a guide projecting from the end of the other handle bar adjacent said blade, a mounting member upon one handle bar, a stop pivoted to said mounting member having a handle at its free end surrounding and slidably
- 45 mounted upon the other handle bar adapted to automatically outstretch during the separation of the handle bars whereby the size of work receivable between said guide and blade is adapted to be limited.
- 50 8. A saw comprising a handle frame embodying bars pivoted at one end to each other, a brace secured to the free end of one bar and engaging the adjacent free end of the other bar to hold the bars spaced in sub-
- 55 stantial parallelism, variable tension means connecting the free end of said bars, and
- an adjustable saw and presser bar guide associated with the free ends of said bars.
9. A saw comprising a handle frame embodying bars pivoted at one end to each other, a brace secured to the free end of one bar and engaging the adjacent free end of the other bar to hold the bars spaced in substantial parallelism, variable tension means connecting the free end of said bars, 60 and means for limiting the opening movement of the bars.
10. A saw comprising a handle frame embodying bars pivoted at one end to each other, a brace secured to the free end of one bar and engaging the adjacent free end of the other bar to hold the bars spaced in substantial parallelism, variable tension means 65 connecting the free end of said bars, an adjustable saw and presser bar guide associated with the free ends of said bars, and means pivoted to one bar and slidably associated with the other bar for limiting the opening movement of the bars.
11. A saw comprising a handle frame embodying bars pivoted at one end to each other, a brace secured to the free end of one bar and engaging the adjacent free end of the other bar to hold the bars spaced in substantial parallelism, variable tension means 70 connecting the free end of said bars, and an adjustable saw and presser bar guide associated with the free ends of said bars, the 75 saw and presser bar guide being adjustable transversely of the end of the handle frame with the longitudinal axis thereof at all times extending in parallel to the axis of the frame.
12. A saw comprising a handle frame embodying bars pivoted at one end to each other, a brace secured to the free end of one bar and engaging the adjacent free end of the other bar to hold the bars spaced in substantial parallelism, variable tension means 80 connecting the free end of said bars, and an adjustable saw and presser bar guide associated with the free ends of said bars, the saw and presser bar guide being adjustable transversely of the end of the handle frame with the longitudinal axis thereof at all times extending in parallel to the axis of the frame.
- 95
13. A saw comprising a handle frame embodying bars pivoted at one end to each other, a brace secured to the free end of one bar and engaging the adjacent free end of the other bar to hold the bars spaced in substantial parallelism, variable tension means 90 connecting the free end of said bars, and an adjustable saw and presser bar guide associated with the free ends of said bars, the saw and presser bar guide being adjustable transversely of the end of the handle frame with the longitudinal axis thereof at all times extending in parallel to the axis of the frame.
- 100
14. A saw comprising a handle frame embodying bars pivoted at one end to each other, a brace secured to the free end of one bar and engaging the adjacent free end of the other bar to hold the bars spaced in substantial parallelism, variable tension means 105 connecting the free end of said bars, and an adjustable saw and presser bar guide associated with the free ends of said bars, the saw and presser bar guide being adjustable longitudinally of the brace with the longitudinal axis thereof remaining at all times at right angles to said brace.
- 105
- In testimony whereof we affix our signatures.
